UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed November 27, 1922. Serial No. 603,449.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in Con-
ductor Supports, of which the following is
a specification.

10 My invention relates to conductor sup-
ports and has particular reference to that
class of support by means of which the trol-
ley wire may be gripped and supported
from an overhead hanger or other similar
device.

15 The object of my invention is to produce
a simple, cheap, efficient and reliable device
which is easy to install, and one in which
the parts are permanently secured together.
Other objects will be disclosed hereinafter.

20 My invention resides in the new and
novel construction, arrangement and combi-
nation of the various parts hereinafter more
fully described and disclosed in the draw-
ing, forming a part of this application.

25 In the drawing:—

Figure 1 shows a side elevation of a de-
vice embodying my invention as secured to
a trolley wire.

Fig. 2 shows an end elevation of Fig. 1.
30 Fig. 3 shows a sectional view of Fig. 1 on
the line 3—3.

Fig. 4 shows a longitudinal view in sec-
tion of Fig. 2 on the line 4—4.

Fig. 5 shows a transverse sectional view
35 with the jaws opened up in position to grip
a trolley wire.

In the preferred form of device embody-
ing my invention I employ a support mem-
ber 1 provided with a threaded recess 2 by
40 means of which the device is detachably
secured to an overhead support. Depending
from the support member 1 is a lug 3 pro-
vided with a channel 4. Secured to the lug
3 by means of a pin 5 are two jaw members
45 6 which are duplicates and each of which
is provided with two lugs 7—7 and 7'—7'
respectively. It will be noted that the lugs
are fixedly pivoted to the supporting mem-
ber 1 so that the lower ends of the jaws
50 which are provided with lips 8 for gripping
the trolley wire are free to move toward and
away from each other. Each jaw is pro-
vided with a projecting arcuate shoulder 9
having a beveled upper surface 10. Mount-

ed on the supporting member 1 is an oper-
ating member 11 having a threaded engage-
ment 12. The lower end of the operating
member 11 is recessed and is provided with
an inner beveled wall 13 which engages with
the outer edge of the shoulder 9 on each jaw. 55

It will be noted that the angles of faces
10 and 13 are made quite different and I
have purposely done this so that with the
varying sizes of wire with which my device
is used, the two faces will not at any time 60
contact throughout, but the contact between
the shoulder 9 and the operating member 11
will be always at the outer edge of the
shoulder 9, and I prefer to have the point of
contact between the shoulder 9 and the op- 65
erating member 11, when the jaws are in
engagement with the trolley wire, below the
axis of the pin 5, and so dimension my de-
vice that with the various sizes of wire with
which it will be used the point of contact 70
between the shoulder 9 and the operating
member 11 will be below the axis of the pin
5 as indicated at A.

At the upper end of the operating mem-
ber 11 I provide a flange 14 to engage with
a flange 15 on the supporting member 1. The
flange 14 is originally in upright position
so that the face 16 of the operating
member can be brought into contact with
the lower face of the flange 15 when the op-
erating member is screwed upwardly a suffi-
cient distance. The flange 14, however, is
adapted to be turned inwardly as shown in
the various figures in the drawing after the
device has been assembled to prevent dis-
sembling as later explained. 85

To assemble the aforesaid described de-
vice, I first assemble the support and oper-
ating members 1 and 11 and bring the shoulder
16 into engagement with the lower face of 90
the shoulder 15. The operating member 11
is so proportioned that its lower edge when
positioned on the supporting member, as
just described, will not extend below the
upper edge of the channel 4 in the support-
ing member. With the operating member
and supporting member assembled as de-
scribed, the two jaws 6—6 are placed in posi-
tion with respect to the lug 3 and channel
4 and the pin 5 inserted into position thereby
pivotally and fixedly mounting the jaws in
relation to the supporting member. The op-
erating member is then screwed down- 100
105

ward until the upper edge of the member 14 clears the lower face of the flange 15 and then the upstanding member 14 is turned inwardly as shown in the drawings until it 5 underlaps the flange 15 thereby limiting the upward movement of the operating member 11 relative to the supporting member as compared with its movement prior to turning the shoulder 14. This will now prevent 10 the lower edge of the operating member 11 from rising above a point in line with the upper edge of the pin 5 and the lower petticoat of the operating member 11 will overlap the pin 5 for a distance indicated by B, 15 thereby preventing the pin 5 from displacement and at the same time avoiding the necessity of riveting the ends of the pin 5. This arrangement also conceals entirely, or to a large degree, the pin 5 which adds to 20 the appearance of the finished device. The flange 14 could be eliminated and the ends of the pin 5 riveted over which would serve to lock the parts permanently together, but I prefer to use the flange 14 as just described 25 or equivalent means.

In assembling my device upon a support and trolley wire, the clamp is first screwed on to the stud of an overhead hanger H by means of the thread 2 as far as possible, and 30 then the lips 8 of the jaws 6 are brought into alignment with the trolley wire. The jaws are then opened up at the lower end and the trolley wire inserted in position and the jaws allowed to fall back until the lips 8 engage 35 the trolley wire. The jaws are now held in position in engagement with the trolley wire and the operating member 11 rotated preferably by hand until it engages with the shoulder 9 on the jaws, thereby holding 40 the jaws in position in engagement upon the trolley wire. This engagement can now be made more secure by applying a wrench to the polygonal faces 17 of the operating member thereby still further rotating the operating member into engagement with the jaws 6, which in turn forces the lips 8 into 45 stronger engagement with the trolley wire.

The advantage of having the contacting point between elements 9 and 13 on a line 50 with or preferably below the axis of the pin 5, or other pivotal point, is that the friction between the parts is kept low and confined almost exclusively to that due to the parts rotating together. If the contact point is 55 above the axis of the pin 5, or other pivotal point, as the jaws pivot about the pin 5, the contact edge of the member 9 will tend to move outward towards the surface 13 thereby bringing an additional friction upon the 60 parts.

If the surfaces 10 and 13 should coincide throughout their height, and since the size of trolley wire varies, there is a probability that the engagement between the members 6 65 and 11 may vary as for instance, the contact

of 6 with 11 may be at times as shown in the drawings, at other times it may be throughout the surface 10 and at other times it may be with the edge 18. By my proposed construction the contact is kept practically uniform and constant. 70

I have shown the hanger H in Fig. 4 only but its attachment to the clamp does not in any way affect the operation of the clamp as the hanger acts merely as a support and the 75 clamp may be secured to the conductor prior to being secured to the hanger H if desired.

Having described my invention as required,

I claim:

1. A trolley wire clamp comprising a support provided with means for attachment to a hanger, a pair of jaws having a pivotal engagement with the support, each jaw having projections and rotatable means on the support to engage the projections at a point below the pivotal engagement of the jaws and support to move the jaws into engagement with a trolley wire. 85

2. A trolley wire clamp comprising a support provided with means for attachment to a hanger, a pair of jaws having a pivotal engagement with the support, each jaw having projections and rotatable operating means to engage the projections below the pivotal engagement of the jaws and support to move the jaws into engagement with a trolley wire. 90

3. A trolley wire clamp comprising a support, a pair of jaws, holding means for maintaining the jaws and support in a fixed pivotal relation, rotatable operating means to engage the jaws and move them into engagement with a trolley wire and means on the jaws below the holding means to engage the operating means whereby the jaws may be moved. 100

4. A trolley wire clamp comprising a support provided with means for attachment to a hanger, a pair of jaws having a pivotal engagement with the support, and each jaw having projections, rotatable operating means to engage said projections to move the jaws into engagement with a trolley conductor, the opposed faces of the projections and the operating means being beveled at different angles to limit the extent of their engagement as described. 115

5. A trolley wire clamp comprising a support provided with means for attachment to a hanger, a pair of jaws having a pivotal engagement with the support, and each jaw having projections, rotatable operating means to engage said projections to move the jaws into engagement with a trolley conductor, and the engagement of the projections and the operating means being below the pivotal engagement of the jaws with the support after the jaws engage the trolley wire. 120

6. A trolley wire clamp comprising a support provided with means for attachment to a hanger, a pair of jaws having a pivotal engagement with the support, and each 5 jaw having projections, rotatable operating means to engage said projections to move the jaws into engagement with a trolley conductor, the point of engagement between the projections and the operating means 10 moving downward and towards the vertical axis of the support as the jaws move towards the trolley wire.
7. A trolley wire clamp comprising a support provided with means for attachment 15 to a hanger stud, a pair of jaws having a pivotal engagement with the support, a pin to maintain said pivotal engagement, rotatable operating means having a threaded engagement with the support to engage the 20 jaws to move them into engagement with the trolley wire, and means on the operating member to prevent the disengagement of the pin.
8. A trolley wire clamp comprising a support provided with means for attachment 25 to a hanger stud, a pair of jaws having a pivotal engagement with the support, a pin to maintain said pivotal engagement, operating means to engage the jaws to move them 30 into engagement with the trolley wire, means on the operating member to be engaged by the pin to limit the longitudinal movement of the pin and means on the operating member to engage the support to prevent the operating means moving out 35 of an engageable position with the pin.
9. A trolley wire clamp comprising a support provided with means for attachment to a hanger stud, a pair of jaws having a pivotal engagement with the support, a pin 40 to maintain said pivotal engagement, operating means to engage the jaws to move them into engagement with the trolley wire, means on the operating member to be engaged by the pin to limit the longitudinal 45 movement of the pin and means to prevent the operating member moving out of an engageable position with the pin.
10. A trolley wire clamp comprising a support provided with means for attachment 50 to a hanger, a pair of jaws having a pivotal engagement with the support and each jaw having projections, a pin to maintain said pivotal engagement, operating means to engage said projections to move the jaws into engagement with a trolley wire, the opposed 55 faces of the projections and the operating means being beveled at different angles to limit the extent of their engagement, the beveled face on the operating member being positioned to be engaged by the pin to limit its longitudinal movement and means to prevent the movement of the operating means from a position to be engaged by the pin. 60
- In testimony whereof I affix my signature. 65

HOMER P. CHANDLER.
